UNITED STATES PATENT OFFICE.

WILLIS A. FOGG, OF MALDEN, MASSACHUSETTS.

PARCEL-DOOR ATTACHMENT.

1,186,565.

Specification of Letters Patent. Patented June 13, 1916.

Application filed June 5, 1914. Serial No. 843,299.

To all whom it may concern:

Be it known that I, WILLIS A. FOGG, a citizen of the United States, and a resident of Malden, in the county of Middlesex and 5 Commonwealth of Massachusetts, have invented certain new and useful Improvements in Parcel-Door Attachments, of which the following is a full, clear, and exact specification.

10 The milkman, because he must come at an early hour, is obliged to leave the milk outside the door. The grocer's boy, if the family happen to be away from home, must take the chances of leaving the articles upon the 15 door-step. The letter carrier, on the other hand, not being permitted to leave parcels where they may be stolen, must await the coming of someone to open the door, and so lose valuable time. This is all highly objectionable, especially in relation to the 20 milk, inasmuch as the same is liable to contamination by cats and dogs; to be frozen in the winter; to be soured in hot weather; or to be stolen by tramps or mischievous 25 boys.

The purpose of this invention is the effecting of comparatively inexpensive and readily applied means whereby an opening may be cut through a panel of the door, 30 preferably at both the front and rear of the house, and such opening may be provided with a hinged leaf having means for fastening. In accomplishing this, I prefer to form two light metal frames adapted to be 35 clamped to the edges of the cut panel and to have the leaf hinged thereto, such leaf being preferably the cut out portion of the panel suitably fitted to the frame, so that there may be no need of expending time and skill 40 in matching the finish of the panel and leaf. I have further so arranged the metal inner frame and outer frame that the same can be fitted to any ordinary thickness of panel without more delay than would be required 45 if all the panels were of exactly the same thickness. The whole contrivance is so planned, therefore, that a canvasser can go from house to house, carrying simply the light metal frames and the hinges, locks, 50 etc., and can in a few moments, with a key-hole saw, cut the panel-opening, attach the inner frame and outer frame, plane down the edges of the cut out section of panel, and affix the other parts. With almost equal 55 ease, a householder can purchase the devices

and directions at a hardware store and fit up his doors therewith.

Referring to the drawings forming part of this specification, Figure 1 is a perspective view of a portion of an ordinary door 60 having my parcel-door attachment applied thereto. Fig. 2 is a vertical transverse section of the same, the parcel door being shown partially open. Fig. 3 is a horizontal section of the same, but with the parcel-door 65 closed. Fig. 4 is a face view of a corner portion of the inner frame and outer frame. Fig. 5 is a sectional detail view on a larger scale of the inner frame and outer frame. Fig. 6 is another detail view of the inner frame. 70

Examining first Fig. 1, the reference numeral 1 designates a portion of the side frame of a door way; to which a door 2 is hinged, the lowest panel 3 thereof being the one preferably selected for the reception 75 of the parcel-door. The parcel-door 4 is here illustrated as hinged to the frame 5 at its upper edge, as by the hinges 6, although I do not restrict myself to such location of the hinges, while its lower edge is provided 80 with a fastening device, as the spring catch 7 adapted to engage the frame member beneath.

The inner frame 5 is preferably of metal, either cast or pressed, and approximately 85 U-shaped in cross section, but with the inner flange 9 longer than the other. This frame comprises four members,—a top, two sides and a bottom member, said bottom member 10 differing from the others in having its flange 90 or web 9 extended and slanted to compose a water-shed 11. The opening through the panel 3 having been cut of a size to loosely fit the webs 9, as shown in Figs. 2 and 3, the short web 12 rests against the surface of 95 the panel around said edges.

For the outer side of the panel, a three-part outer frame 13 is provided, consisting of a top member and two side members, adapted to fit within the frame 5 and rest 100 against the face of the panel, while its inner flange 14 serves as the door-jamb for the leaf 4. For fastening said inner frame and outer frame in place, small bolts 15 are provided, the heads 16 of which are not slotted but are formed with two holes 17 for engagement by a two-spurred screw driver, in order that they may not be unscrewed by tramps or boys. The nuts 19 of these bolts fit snugly between the webs 9 and 12 of the 110

frame 5, and are slightly tapered, as shown in Fig. 5, so that they can be fixed in the frame by suitably setting in short sections of the edge of the web 12. No screws will 5 appear when the frame is viewed from within the house, since the screw heads are all introduced from the latter side, and the screw points are within and concealed by the frame 5. Where the frames are of metal, 10 the screws 15 engage nuts held within the frame 5; but if it is desired to make the frames of wood, such nuts are dispensed with and the screws turn in the wood itself.

The cut out section of panel having been 15 planed off to true up its edges and to fit it within the frame 5, hinges 6 are fastened to the top member of the frame by small bolts 20 penetrating slots 21 (Figs. 2 and 6), and then screwed to the top edge of the leaf 20 4. Said slots permit the leaf to be adjusted to close snugly against the door-jamb 14, after which adjustment the bolts are tightened up. A spring catch 7 is attached to the 25 lower end of the leaf 4, upon its inner face, to engage a notch 22 in the bottom frame member.

For closing the leaf 4 from the outside, 30 a hand-grip 23 is attached to the outer surface thereof, the upper side of which grip is made slanting, as shown in Fig. 2, in order that a parcel slipped in through the opening may not catch upon the hand-grip.

I prefer to form the spring catch 7 with 35 two engaging points one in advance of the other, the point 24, which is the first to reach the notch 22 as the leaf or parcel-door 4, being oblique on both faces, while the point 25 is parallel with said door at its inner face. Hence by partially shutting the 40 parcel-door so that said oblique point engages the notch 22, said door is held against swinging open under the pressure of the wind, or of a cat, but it can be easily pushed open by the letter carrier, or delivery boy, or milk man, and the parcel, packages, or 45 milk jar can be handed through the opening and left upon the floor. After such delivery, and especially after the delivery of mail matter, the parcel-door is pulled to its 50 closed position and the point 25 engages the notch 22. This locks the said leaf or door against the possibility of the theft of the delivered articles.

For the back and side doors of houses, the 55 above-described construction is sufficient, but for the front doors, I prefer to provide the parcel-door with a lock 26, the key 27 of which is to be carried by the letter carrier and by no one else. This lock is preferably 60 connected with the spring catch 7, so that it need not interfere with the above-described manipulation of the latter.

For the front door, I further provide the 65 parcel-door 4 with a letter slit 30 of substantially well known arrangement, the slot

through the wooden leaf being surrounded by metal plates 31, 32, the outer one 32 having a flap 33 of usual construction. While this letter slit is of value in permitting the letter carrier to leave letters without 70 unlocking the parcel-door, said plates serve also to strengthen the leaf 4 and to keep it from warping, in case the grain of the wood is vertical in general direction. Moreover, the letter slit permits of the hand-grips being dispensed with, since the letter carrier can pull the parcel-door shut by seizing the 75 edge of the said slit.

Although I have shown the inner frame and outer frame for the parcel-door in Figs. 80 2 to 6 as being composed of metal, yet said parts can readily be made from wood, as indicated in Fig. 1.

While this parcel-door is specially designed for enabling the milkman to put the 85 milk-jar through the house door and to leave the same upon the floor within the house; to accommodate the delivery boy in leaving the smaller articles of merchandise and foods; and to enable the letter carrier to leave with 90 perfect safety the articles sent by parcel post, it is also well adapted for permitting the pet cat or dog to leave the house, and more easily to return at any time in the night or day. If the family live upstairs, a cord 95 can be attached to the parcel door and run to the upper floor, so that by pulling upon such cord the parcel-door can be opened wide and the cat or dog permitted to pass through.

Although I have described and shown my 100 parcel-door attachment as applied to an ordinary house-door, it is evident that it may also be utilized for other places, as for a thin partition, a wooden panel substituted 105 for a pane of glass, and the like.

What I claim is:

1. The combination with a door having a 110 rectangular opening through it, of an inner frame comprising a top, a bottom and two side members, the top and side members having flanges resting against and fastened to the inner surface of the door, and the bottom member projecting through the door to the outside, an outer frame comprising a top and two side members each having a 115 flange resting against and fastened to the outer surface of the door, the lower ends of the side members of the outer frame resting upon said bottom member, and a parcel-door hinged to the top member of the inner frame and having a fastening device engaging 120 said bottom member.

2. The combination with a panel having an opening through it, of a metal inner frame the members of which are U-shaped 125 in cross section, an outer frame, tapered nuts in the hollow of said inner frame and held therein by the slightly inturned edges thereof, bolts passing through said outer frame and engaging said nuts and serving to clamp 130

firmly together the said inner frame, outer frame and the edges of the panel-opening, and a parcel-door hinged to said inner frame.

3. The combination with a panel having an opening through it, of an inner frame comprising a top, bottom and side members, the bottom member having a water-shed extending beyond the outer face of the panel, an outer frame comprising top and side members, means clamping said inner frame and outer frame firmly against opposite

faces of the panel about said opening, and a parcel-door hinged to said inner frame to swing inward.

In testimony that I claim the foregoing 15 invention, I have hereunto set my hand this 1st day of June, 1914.

WILLIS A. FOGG.
